UNITED STATES PATENT OFFICE.

HALSEY W. TAYLOR, OF WARREN, OHIO.

DESIGN FOR A DRINKING-FOUNTAIN BOWL.

53,227.

Specification for Design.

Patented Apr. 22, 1919.

Application filed February 15, 1919. Serial No. 277,367. Term of patent 14 years.

To all whom it may concern:

Be it known that I, **HALSEY W. TAYLOR**, a citizen of the United States, residing at Warren, in the county of Trumbull and State of Ohio, have invented a new, original, and ornamental Design for Drinking-Fountain Bowls, of which the following is a specification, reference being had to the accompanying drawing, forming part thereof.

Figure 1 is a plan view, Fig. 2 a side elevation, and Fig. 3 an end view of a drinking fountain bowl showing my new design.

I claim:

The ornamental design for a drinking fountain bowl, as shown.

HALSEY W. TAYLOR.
